HIGHWAY GATE

William J. Buford, Houston, Tex.

Application July 26, 1937, Serial No. 155,621
Renewed March 22, 1940

5 Claims. (Cl. 39—7)

The invention relates to a highway gate which is particularly adaptable for use in protecting railroad crossings and other intersections. The invention comprehends improvements in the invention of my copending application, Serial No. 142,757, filed May 15, 1937.

A primary object of the invention is to provide a device of the character described that is highly efficient and is economical to construct and install.

It is also an object to provide a device of the class described which will stop vehicles at a point where the stoppage of such vehicles is essential.

A still further object is to provide a device of the character described which will automatically resist the impact of a vehicle therewith and bring the vehicle to a stop, regardless of its weight or speed.

A further object is to provide a device which is so constructed that the rate of absorption of the impact energy will be progressively increased as the gate is displaced from its normal position.

A more specific object is to provide a gate wherein a plurality of weights are sequentially lifted when the gate has moved laterally from its normal position, the arrangement and relative sizes of the weights being such that the rate of absorption of the energy of the impact is progressively increased.

A further object is to provide a construction whereby the proper alignment of the cable with the cable sheaves will be maintained when the gate is displaced from its normal position.

Other objects, together with the foregoing, will be apparent from the following description in which:

Fig. 1 is a vertical sectional view showing the general arrangement of the device of the invention as positioned across the highway.

Fig. 2 is a sectional plan view taken on line 2—2 of Fig. 1.

Fig. 3 is a top plan view of the support frame of the device of the invention.

Figs. 4 and 5 are sectional views showing details of the clamps between the lifting cables of the gate.

In Fig. 1 the surface of the roadway is shown at 1, vertical supports 2 and 3 being fixed in the subgrade 4 at opposite sides of the roadway. Supports 2 and 3 extend upwardly a sufficient distance that the gate 5, which is movably mounted therebetween, may be elevated to a sufficient height to permit the passage of vehicles over

the roadway 1. Frame work 6, 6' are secured to the front and rear of the supports 2 and 3 and form a housing within which the gate 5 is located when in open or elevated position. This frame work at the same time provides display areas upon which any desired information may be displayed. Each of the supporting posts 2 and 3 is provided with a cap member 7, which is affixed thereto as by set screws 8, as best seen in Fig. 3. These cap members are interconnected through a cable 9 and a turn buckle 10 whereby a unitary and rigid frame work is provided. The rigidity of this frame work is enhanced and the frame work is fixed in position by guy wires 11 provided with turn buckles 12 so that adjustment thereof may be effected.

To the right of the roadway as shown in Figs. 1 and 2, is provided a driving motor 16 which is adapted to be energized from any suitable source (not shown) to be rotated in either direction in order to drive drums 17 and 18 through a worm gear, generally designated at 20. These cables 21 and 22 are wrapped about drums 18 and 17, respectively, and hence may be driven thereby because of frictional contact with the drums. It is obvious, however, that, if desired, the cables 21 and 22 may be centrally anchored to their respective drums whereby the possibility of slippage is avoided. Cable 21 passes from drum 17 to and beneath the sheaves 23, 30 which are suitably journaled in bearings 26. In proximity to sheaves 23 are shown three spaced supports 25, which are respectively provided with a pair of cable guiding sheaves 30. It is understood that while three supports are shown, this number is arbitrary, as any suitable number may be used whereby the objects of the invention are realized.

The invention also comprehends passing of cable 21 over sheaves 23 and downwardly into suitable weight receiving wells whereby the construction now to be further described will be below the plane of the roadway 1. It is also apparent that the driving motor 16 and its associated elements may be installed at a level below the roadway whereby only the gate and its supports extend above the surface of the roadway.

Supports 25 are in such spaced relation that weights 31 and 32 may be freely suspended therebetween on the cable 21 which successively passes over the sheaves 30 and beneath the pulleys 33 of the weights. Attention is here directed to the fact that the weights 31 and 32 are of different masses in order that the resistance to

impact of the vehicle against the gate 5 will be progressively increased as the gate is displaced from its normal position. As is clearly shown in the drawings, the weights 31 and 32 5 are made up of sections so that any desired number of weight sections may be added to attain desired relative sizes. Since the weights 31 and 32 are of different sizes it is obvious that the heavier weight will descend and rest upon the 10 ground surface 35, the other weight being suspended to maintain the cable 22 taut and to initially resist the impact of a vehicle against the gate 5.

From the sheaves 30 on supports 25 cable 21 15 passes beneath the sheaves 36 and 37. From sheave 36 the cable passes upwardly within the support member 3 to an upper sheave 38 over which the cable passes and thence downwardly to sheave 37, as above pointed out. The portion 20 of the cable between sheaves 37 and 38 passes in front of guiding sheaves 40 and 41, mounted upon sheave supporting extensions 42 which may be made integral with the support 3 or may be 25 adjustably secured thereto. These guiding sheaves do not normally make contact with the cable 21, but are so positioned that the cable will be forced into contact with the guiding sheaves when the gate 5 is displaced from its normal position between the support members 30 2 and 3. In such event the guiding sheaves 40 and 41 guide the cable relative to the sheaves 37 and 38, respectively.

As the equipment associated with support 2, drum 18, and cable 22, is identical to that just 35 described, a separate description thereof is not believed necessary. Suffice it to say, that cable 22 passes about drum 18 and beneath sheaves 19, thence through a suitable conduit or conduits beneath the roadway 1 to sheaves 23' on 40 the side of the roadway opposite the driving motor 16. Similar parts of this portion of the device are identified by similarly primed reference characters in order that the construction and operation thereof will be apparent from the 45 above description.

Gate 5 is attached to the cables by clamping means which are best shown in Figs. 4 and 5. The top clamp 50 has one end secured to the frame 51 of the gate 5 by means of the clamping 50 bolts 52 (see Fig. 4) while the opposite end of the clamp is fixed to the cable by means of clamping bolts 54 and the wing nuts 55. The lower clamp 56 at the end of the gate is clamped to the gate frame in a manner similar to that 55 described in connection with clamp 50. This clamp, however, carries a roller 56 within a loop 58 wherein the pin 59, upon which the roller 57 is rotatably mounted, is so positioned that the cable 21 may move axially relative to the 60 clamp. In this manner the cable between the clamps 50 and 56 will be taut all times. Each end of the gate is connected to its adjacent cable in the manner just described.

In the operation of the device cables 21 and 65 22 are driven in the proper direction by means of motor 16. If, for example, it is desired to lower the gate 5, motor 16 will be driven so as to drive the cables 21 and 22 in the direction indicated by the arrows. It is to be understood 70 that suitable means, either manual or automatic, will be provided to terminate the movement of the gate when it reaches the desired position between sheaves 40, 40' and 41, 41'. In a similar manner, upward movement will be 75 terminated when the gate has reached the up-

per limit of travel. The associated mechanism may comprise an element of an electric signal system, which is operated by the approach and recession of a train or it may be operated by the entry and exit of a train from a block in which the installation is made. Such system forms no part of the present invention as systems are well known.

When the gate is in closed position it will be assumed that a vehicle comes into contact therewith and the gate is moved transversely from its normal position. The initial impact will be resisted by virtue of the lighter of the weights on the respective cables. These lighter weights will resist the impact with a force which is dependent upon the mass of the weight and the rate of acceleration of the weight by the impact. When these weights approach a position between adjacent sheaves 30 the tension on the cables will pick up the successively heavier weight and the resistance to impact and hence the deceleration of the vehicle will therefore be increased. It is obvious that the lengths of the cables 21 and 22 will be such that a vehicle will be stopped before the weights have reached 25 their limit of travel.

From the foregoing it is apparent that the device serves to progressively increase the force which brings the vehicle to a stop and hence destructive force to both the device of the invention and the vehicle to be stopped thereby are reduced to a minimum. It is to be understood, as has been above indicated, that the number and size of the weights to be used is not limited but that such matter lies within the 35 province of the skilled artisan, the preferred embodiment of the invention as described being merely illustrative.

What is claimed is:

1. A device of the character described comprising spaced vertical supports on opposite sides of a roadway, a frame construction connecting the tops of said supports to form a housing having display surfaces, spaced guide rollers on each of said vertical supports, an endless cable passing over said guide rollers and having a portion thereof extending downwardly along each of the supports, a gate member between said supports and having each end connected to one of said cables, drum means about which each of said cables is passed to be driven thereby, motor means for driving said drum means, paired cable supporting sheaves in spaced relation between each of the vertical supports and said drum means, and a plurality of weights of differing masses supported on each of said cables between the cable supporting sheaves, whereby the cables are maintained taut and the resistance to impact transversely of the gate will be progressively increased.

2. A device of the character described comprising spaced vertical supports, spaced guide rollers on each of said supports, an endless cable member passing over the guide rollers on each of said supports, a gate member between said supports and having its ends connected to said cables, drum means about which each of said cables passes and is adapted to be driven thereby, means for driving said drum means whereby the gate may be raised or lowered, and a plurality of weights supported by each of said cables whereby an impact transversely of the gate will be progressively absorbed by the weights.

3. A device of the character described comprising spaced vertical supports, spaced rollers

on each of said supports, an endless cable passing over the rollers on each of said supports, a gate member between said supports and connected to said cables, drum means about which each of said cables passes whereby the cables may be driven thereby, means for driving said drum means to raise and lower said gate, and a plurality of weights of different masses sheaved upon said cables between the supports and drum means whereby resistance to displacement of the gate by impact therewith will be progressively increased.

4. A device of the character described comprising in combination a gate member, an endless cable connected to the gate at each end, vertical support posts at the ends of the gate, spaced means on said support posts for guiding the cable and gate axially of said support posts,

means for driving said cables whereby the gate may be raised or lowered, and means intermediate said support posts and the last mentioned means for applying a progressively increasing force to each flight of the cables as the gate is displaced transversely from its normal position. 5

5. A device of the character described comprising in combination spaced vertical supports, a gate member between said supports, a cable member connected to said gate at each end, 10 means on said supports for guiding said cables, drum means about which said cables are directed, motor means for driving the drum means to raise and lower said gate, and weight members of different masses upon each of said cables to 15 progressively resist movement of the gate transversely of the plane of the vertical supports.
